UNITED STATES PATENT OFFICE

115,436

DESIGN FOR A CLOCK CASE

Othneil G. Williams, Winsted, Conn.

Application April 4, 1939, Serial No. 84,035

Term of patent 3½ years

To all whom it may concern:

Be it known that I, Othneil G. Williams, a citizen of the United States and a resident of Winsted, in the county of Litchfield, State of Connecticut, have invented a new, original, and ornamental Design for a Clock Case, of which the following is a specification, reference being had to the accompanying drawing, forming part thereof.

Fig. 2 is a side view of the same; and
Fig. 3 is a top view of the same.

I claim:

The ornamental design for a clock case, as shown.

OTHNEIL G. WILLIAMS.
